UNITED STATES PATENT OFFICE.

WILLIAM TOWERS, OF CHRISTOPHER, ILLINOIS, ASSIGNOR OF FORTY-FIVE ONE-HUNDREDTHS TO ROY LOCKRIDGE, OF CHRISTOPHER, ILLINOIS.

MINE-CAR COUPLING.

1,150,980.

Specification of Letters Patent. Patented Aug. 24, 1915.

Application filed May 27, 1914. Serial No. 841,329.

To all whom it may concern:

Be it known that I, WILLIAM TOWERS, a citizen of the United States, residing at Christopher, in the county of Franklin and

5 State of Illinois, have invented new and useful Improvements in Mine - Car Couplings, of which the following is a specification.

The invention relates to couplers, and more particularly to the class of mine car 10 couplers.

The primary object of the invention is the provision of a car coupler of this character wherein two cars may be automatically coupled while in motion without the aid of any 15 person to adjust the same, thereby obviating any possibility of injury to a person, as the necessity of stepping between the cars for the coupling thereof is obviated.

Another object of the invention is the 20 provision of a coupler of this character wherein the male and female members of the coupler serve as buffers to obviate undue shocks and jars to the cars incident to the coupling thereof, which is automatically 25 effected on the approach of the cars toward each other.

A further object of the invention is the provision of a coupler of this character wherein the male and female coupling members 30 are of novel form and are supported upon each car in a novel manner.

A still further object of the invention is the provision of a coupler of this character which is simple in construction, reliable and 35 efficient in use, strong, durable, and inexpensive in manufacture.

With these and other objects in view, the invention consists in the construction, combination and arrangement of parts as will 40 be hereinafter fully described, illustrated in the accompanying drawings, and pointed out in the claim hereunto appended.

In the drawings:—Figure 1 is a fragmentary side elevation of adjoining cars, showing 45 the coupler constructed in accordance with the invention applied and the cars coupled together. Fig. 2 is a bottom plan view of the coupler. Fig. 3 is a horizontal sectional view through the coupler. Fig. 4 is a 50 perspective view of the coupling pin. Fig. 5 is a vertical sectional view through the truck frames of the cars and coupler. Fig. 6 is a perspective view of the male coupling member. Fig. 7 is a perspective view 55 of the female coupling member. Fig. 8 is a

vertical transverse sectional view through the female coupling member, showing an elevation of the coupling pin in locking position.

Similar reference characters indicate corresponding parts throughout the several views in the drawings.

Referring to the drawings in detail, A and B designate portions of adjoining mine cars, and C and D respective male and female 65 members of the coupling between the cars, the said coupling being hereinafter fully described.

At each end of the truck frames of the cars are the usual cross bolsters 10, between 70 which work the male and female members C and D which are respectively located at opposite ends of each car centrally of its truck frame.

The male member C of the coupling comprises a solid head 11 which is formed with a draw bar 12 provided with a vertical elongated slot 13 through which is passed the king bolt 14 mounted in the bolsters 10. Surrounding the draw bar 12 at opposite 75 sides of the king bolt 14 are coiled compression springs 15, one of which bears against the head 11, while its opposite end works against a washer 16 next to the king bolt 14, while the other spring has one end working against a substantially U-shaped yoke 17, the ends of which are bolted or otherwise fixed to the head 11 of the male member, while the opposite end of the said last-named spring works against a washer 18 85 next to the king bolt 14, and these springs serve to absorb shocks and jars incident to the coupling of the male member with the female member of the coupling in a manner presently described. 90

The head 11 of the male member C of the coupling is formed with a tongue 19 formed in opposite edges with directly opposed notches 20 and with a spear-shaped tip 21, the said tongue being adapted to enter the 100 female member D of the coupling for the joining of the same in a manner presently described.

The female member D of the coupling comprises a socketed head 22, the socket 105 therein being adapted to receive the tongue 19 on the head of the male member, and this head 22 is further formed with a draw bar 23 provided with a vertical elongated slot 24 through which is passed the king bolt 25, 110

the same being engaged in the cross bolsters 10 of the truck frame of the car. Surrounding the draw bar 23 are coiled compression springs 26, the ends thereof next to the bolt 5 being designed to work against washers 27, while the opposite ends work against the respective head 22 and the substantially U-shaped yoke 28 having its ends fixed to the said head 22, the springs being designed to 10 absorb shocks and jars incident to the coupling of the cars together. It will be noted that by the particular mounting of the draw bars of the male and female members C and D of the coupling the same are free for 15 swinging movement to permit the coupled cars to take sharp or wide curves in the track and to allow for lateral thrust of the cars during their travel.

In the head 22 of the female member D 20 are formed openings 29 in the top and bottom walls thereof to receive a coupling pin E, which comprises a forked member 30, the limbs of the fork being adapted to pass through the openings 29 in the head 22 to 25 engage in the notches 20 in the tongue 19 at opposite sides thereof, the inner sides of the limbs of the fork 30 being formed with beveled shoulders 31 which are adapted to engage with the spear-shaped tip 21 to lock 30 the tongue in the socket in the head 22 of the female member so that the male member will be joined thereto. The forked member 30 has a central bifurcated portion 32 which receives the web between the openings 29 in the top upper wall of the head 22, so that when the male and female members C and D are uncoupled and the cars are brought together, on the entrance of the tongue 19 in the socket in the head 22 the 35 spear tip 21 will engage the shoulders 31 of the pin E for lifting the same so that it will automatically lock with the tongue 19 for the uniting of the male and female members of the coupler. When the pin E is raised 40 the limbs of the fork 30 thereof will permit the passing of the spear-tip 21 therebetween so that on the lowering of the pin by its 45

own weight the shoulder portions 31 will engage the notches 20 in the tongue 19 to firmly lock it within the socket in the head 50 22 of the female member of the coupling.

The heads 11 and 22 of the members of the coupler at their top are formed with external enlarged portions 33 which form stops to engage the cross bolsters 10 to limit 55 the inward movement of each member of the coupler when the cars move toward each other during the act of coupling the same together, and thus relieving undue strain on the springs absorbing the shocks and jars 60 incident to the coupling of the cars.

The pin E can be raised in any suitable manner when it is desired to uncouple the cars.

From the foregoing it is thought that the 65 construction and manner of operation of the device will be clearly understood, and therefore a more extended explanation has been omitted.

What is claimed is:—

A coupling comprising a pair of heads having flat faces adapted for contact with each other, one of the heads being formed with a recess having an inwardly tapered inner end, a spear shaped tip having a shank 75 integrally formed with and extending from the other head and received in the recess for its seating in the tapered inner end thereof, said tip being formed with laterally extending reversely beveled portions at its upper 80 side, and a fork-like slide mounted in the recessed head and intersecting its recess and formed with shoulders on opposite limbs for engagement with the beveled portions to automatically operate the said slide on the 85 insertion of the tip in the recessed head to fasten both heads together.

In testimony whereof I affix my signature in presence of two witnesses.

WILLIAM TOWERS.
